Atty.

UNITED STATES PATENT OFFICE

HILDA H. CADY, OF SARANAC LAKE, NEW YORK

HAIR WAVER

Application filed January 25, 1930. Serial No. 423,486.

This invention relates to devices used in forming water waves in the hair.

The object of the invention is to provide a water wave device by means of which the hair will be held and prevented from slipping through the device.

A further object of the invention is to provide a water wave device by means of which a flat perfect wave is produced.

10 Referring to the accompanying drawing:—

Figure 1 is a perspective view of the invention.

15 Figure 2 is a side view of the invention. Figure 3 is an enlarged detail section on the line 3—3 of Figure 2.

In carrying out the invention a pair of spring arms 1 and 2 are provided which when not in use are slightly separated and 20 connected at one end by a spring hinge 3 whereby the strips may be drawn together and held in clamped position by suitable fastening means as, for example, the end 4 of one strip engaging the inturned end 5 of the other strip, the parts so related as to be able to be snapped into locked position. The device is preferably formed of a single strip of steel to provide the resilient or 25 spring strips 1 and 2 and the hinge 3. In 30 use the hair to be waved is clamped between the strips 1 and 2 which are held together in locked position.

In order that the hair held by the strips shall not slip between them when the hair 35 is combed back and forth the strip 1 is formed with teeth 6 projecting from its under side, the teeth 6 extending in a line from one end of the strip to the other and the strip 2 is formed on its upper side with a line 40 of depressions or sockets 7 which when the strips are clamped together receive the teeth 6.

It will be noticed that the teeth 6 are 45 spaced apart from each other as are depressions or sockets 7 in the strip 2.

By means of the foregoing construction the individual hairs are firmly held in place between the teeth and the sockets which are clamped together as shown by dotted lines 50 in Fig. 3. The strips are formed flat which

with the teeth and sockets when clamped together serve to produce a perfect flat swirl back and forth over the head, that is the true water wave, without forming a ridge in the hair.

55 The device is used as follows: The hair is first dampened and combed smoothly back. The lower strip of the device is then inserted along the scalp and clamped against the upper strip. The hair is now held firmly in place and will not slip forward or backward in the device when the hair is combed forward or backward.

With one hand steady the device by means 60 of a slight pressure to the head and with the other hand comb the hair forward inserting another similar device as before. Comb the hair back again this time steadyng the second device.

65 Repeat combing the hair backward and forward inserting as many devices as there are waves desired.

The device is preferably made of thin 70 spring steel, five inches long and curved slightly to fit the head; the depressions or sockets which are preferably punched in the metal are about one-eighth inch apart as also the teeth.

75 The foregoing specification and annexed drawing disclose the preferred embodiment of my invention, but it is to be understood that minor changes may be resorted to in the commercial adaptation of my invention without departing from the scope of the invention as claimed.

80 What I claim is:—

1. A device of the kind described comprising elastic clamping strips provided with interengaging spaced teeth and sockets, and flat surfaces between said teeth and sockets, whereby the individual strands of hair will be held firmly in place when the hair is combed backward and forward to form the wave.

95 2. A device of the kind described comprising elastic clamping strips having a longitudinal line of interengaging spaced teeth and sockets, and flat surfaces between said teeth and sockets, whereby the individual strands of hair will be held firmly in place 100

when the hair is combed backward and forward to form the wave.

3. A device of the kind described comprising curved spring clamping strips having a line of interengaging spaced teeth and sockets, and flat surfaces between said teeth and sockets, whereby the individual strands of hair will be held firmly in place when the hair is combed backward and forward to form the wave.

4. A device of the kind described comprising a pair of spring actuated curved clamping strips, one of said strips having a line of spaced sockets and the other a line of spaced teeth engageable with said sockets, and flat surfaces between said teeth and sockets, whereby the individual strands of hair will be held firmly in place when the hair is combed backward and forward to form the wave.

5. A device of the kind described comprising a pair of curved spring actuated clamping strips formed of a single strip of steel, one of said strips having a line of spaced sockets and the other a line of spaced teeth engageable with said sockets, and flat surfaces between said teeth and sockets, whereby the individual strands of hair will be held firmly in place when the hair is combed backward and forward to form the wave.

6. A hair waver comprising curved spring clamping strips, one of said strips having a line of punched spaced sockets and the other a line of spaced punched teeth engageable with said sockets, and flat surfaces between said teeth and sockets, whereby the individual strands of hair will be held firmly in place when the hair is combed backward and forward to form the wave.

40 7. A hair waver comprising a pair of elastic curved spring clamping strips hinged at one end and having fastening means at the other end, one of said strips having a line of spaced sockets and the other a line of spaced teeth adapted to engage said sockets, and flat surfaces between said teeth and sockets, whereby the individual strands of hair will be held firmly in place when the hair is combed backward and forward to form the wave.

55 8. A device of the kind described comprising clamping strips provided with interengaging spaced teeth and sockets, and flat surfaces between said teeth and sockets, whereby the individual strands of hair will be held firmly in place when the hair is combed backward and forward to form the wave.

In testimony whereof I hereunto affix my
60 signature.

HILDA H. CADY.
